UNITED STATES PATENT OFFICE.

WILLIAM G. BARNARD, OF SOMERVILLE, MASSACHUSETTS.

ENDLESS BELT.

1,411,602.

Specification of Letters Patent. Patented Apr. 4, 1922.

Application filed February 10, 1920. Serial No. 357,764.

To all whom it may concern:

Be it known that I, WILLIAM G. BARNARD, a citizen of the United States, residing at Somerville, in the county of Middlesex and 5 State of Massachusetts, have invented certain new and useful Improvements in Endless Belts, of which the following is a specification, which improvements were shown, described, and claimed in an abandoned application filed by me June 4, 1917, Serial 10 Number 172,615.

My invention relates to endless belts, and particularly to endless power transmitting belts. Most endless power transmitting 15 belts as heretofore constructed have not been satisfactory for the reason that they would quickly wear out when driven at high speed, and also because after a short period of use they would stretch. Usually, also, the joint 20 connecting the ends of the strap from which the belt was constructed made the belt thicker at the joint than at other points with the result that the belt would pound on the pulleys resulting in stretching and 25 quick wear.

My invention has for its object to provide a flexible endless belt of improved construction and particularly to obviate the objections noted above.

30 The invention consists of an endless belt embodying the peculiar features of construction set forth in the following description and particularly pointed out and defined in the claims at the close thereof.

35 In the accompanying drawings:

Figure 1 is a perspective view of a belt constructed in accordance with my invention.

Figure 2 is a longitudinal sectional view 40 of the belt shown in Fig. 1.

Figure 3 is a section on line 3—3 of Fig. 1.

Figure 4 is a fragmentary sectional detail drawn upon a very much enlarged scale.

That form of my invention herein shown 45 includes two bands of textile woven fabric 1 and 2 arranged one within the other and fastened together by cement 3 which is forced more or less into the interstices of the two fabrics by pressure. In practice I prefer 50 to employ a cement which will remain flexible after drying, a special cement of this kind having been produced by me for this purpose the making of which it is unnecessary for me to describe here. This use of a 55 dry flexible cement between and uniting the

two bands is, however, a feature of my present invention.

In the preferred form of my invention each band 1 and 2 is made from a length of woven tape having a selvage at each edge, 60 said tape being produced by the well known "herring bone" weave which gives the belt a surface which grips the pulleys better than a plain weave.

The ends of each band 1 and 2 are formed 65 with oppositely oblique edges and after being brought together edge to edge as indicated at 4 they are cemented to a relatively thin and narrow textile tape 5 laid obliquely in position on the band so as to cover the 70 joint 4 and overlie both ends of the band, the ends of said tape being wrapped around the side edges of the band and cemented to the opposite side of the latter. After applying the tapes 5 to the bands 1 and 2 cement 75 is applied to the exterior of the band 2 and to the interior of the band 1 after which the band 2 is placed within the band 1 and the two are pressed together. As will be clear 80 from Figs. 1 and 2 the two bands are assembled with the two joints 4 separated, or staggered relatively, so that each is opposite the body portion of the other band, the ends of each band, the ends of its tape 5, and the body portion of the latter, being then sewed 85 together and to the other band by two short longitudinal lines of through-and-through stitches 7 and 8.

My improved belt is of simple and inexpensive construction and requires no metal 90 parts. It is uniformly flexible and strong, durable, and particularly adapted for high speed work, and in situations where it is necessary that the belt withstand hard and continuous usage.

By using bands 1 and 2 woven with selvages at both sides I avoid the objectionable folding and longitudinal stitching necessary 95 with textile belts as heretofore constructed in order to prevent the side edges from fraying. For the purposes of illustration Fig. 2 indicates a thickening of the belt at the joints 4 but as a matter of fact the tapes 5 are, in practice, so thin that they do not 100 visibly increase the thickness of the belt at these points. Therefore, the joints of my improved belt do not pound or cause increased tension in passing over the pulleys so that said belt runs smoothly and under uniform tension. Moreover, the particular 105

method described above of connecting the ends of each band together by sewing and cementing them to the adjacent body or intermediate portion of the other band, not 5 only provides a very strong and serviceable joint which is as flexible as any other portion of the belt, but also encloses the ends of the threads at the ends of each band so that they cannot fray or ravel.

10 What I claim is:

1. An endless belt of the character described comprising two bands each of which is a strip of textile material having parallel oblique end edges abutted one against the 15 other; means fastening said bands together, one inside of the other to form a unitary flexible belt structure having the joint of one band staggered relatively to the joint of the other band; and an obliquely trans- 20 verse strip of textile material upon the exterior side of each band overlying the joint at said abutting ends; said strip having its ends folded around the sides of its band and extending in between the two bands, 25 and means fastening said strip to its band.

2. An endless belt of the character described comprising two bands arranged one within the other, each of said bands being a strip of textile material having parallel oblique end edges abutted one 30 against the other; means fastening said bands together to form a unitary and flexible belt structure having the joint of one band staggered relatively to the joint of the

other band; a piece of textile material upon the exterior side of each band overlying the joint at said abutting ends, said piece having portions thereof folded around the sides of its band and extending in between the two bands, and means fastening said piece 40 to its band.

3. An endless belt of the character described comprising two bands arranged one within the other, each of said bands being made up of a strip of textile material having its ends brought together opposite each other; means fastening said bands together with the joints between their ends staggered relatively to form a unitary flexible belt structure; a transverse piece of 45 textile material for each band overlying the joint between the ends thereof, and means fastening said piece to both ends of its band.

4. An endless belt of the character described comprising two bands arranged one within the other, each of said bands being made up of a strip of textile material having its ends abutting one against the other; means fastening said bands together to form 50 a unitary flexible belt structure; a transverse piece of textile material upon the exterior side of each band overlying the joint at said abutting ends, and means fastening said piece to both ends of its band.

In testimony whereof I have affixed my signature.

WILLIAM G. BARNARD.
